(57) **CLAIM**

The ornamental design for a car wheel, as shown and described.

DESCRIPTION

FIG. 1 is a front perspective view of a car wheel showing my new design.

FIG. 2 is a front view of a car wheel showing my new design.

FIG. 3 is a right side view of a car wheel showing my new design.

FIG. 4 is a left side view of a car wheel showing my new design.

FIG. 5 is a top plan view of a car wheel showing my new design; and,

FIG. 6 is a bottom plan view of a car wheel showing my new design.

The broken line showing of the four groups of four elements on the rim in FIGS. 1-6 and of the rear and side of the rim in FIGS. 1, and 3-6 is included for the purpose of illustrating environment and forms no part of the claimed design.

1 Claim, 4 Drawing Sheets

FIG. 1
